STAIR CARPET, PAD, AND THE LIKE

Kenneth J. McKenzie, Chicago, Ill.

Application October 3, 1934, Serial No. 746,757

1 Claim. (Cl. 154—56)

This invention relates to improvements in stair carpets, pads, and the like, and, more especially, to improved means for attaching the same to the treads and risers of a stairway.

5 It has been found heretofore that the carpeting of a stairway requires considerable expense, both for labor and material. The latter item alone is ordinarily rather large because of the long single strip or piece of carpet required for covering a stairway in the manner heretofore in use.

10 One of the principal features of my invention is the saving of great expense in material by employing a number of small pieces of carpet for the purpose. This permits the use of remnants and odds-and-ends and thus effects a great saving in cost of material.

15 By the use of my invention, I am also able to save expense in the item of labor. By the use of my invention, the separate pieces of carpet and the pads can be easily and quickly applied.

20 By the use of my invention, a great variety of new effects can be obtained. In the first place, it is possible to cover a stairway completely with pieces all of the same material and color so that 25 when complete, the stairway has the appearance of being covered by a single strip of material as in the past. Consisting of separate pieces, however, there is a great saving in the cost of material. Besides this, if desired, the carpeting of 30 the risers may be omitted, applying separate pieces of carpet and pads to the treads alone. There is thus effected a great saving in the quantity of material required. If desired, the treads and risers can both be covered, using 35 material of different colors or kinds on the risers from that used on the treads. This arrangement can be employed to give new and unusual effects. Also, it is obvious that, in the practice of my invention, a great variety of combinations of colors, 40 materials, and the like, may be used on the treads and risers themselves. In fact, it is possible to incorporate particular designs, lettering, wording, advertising matter, and the like, in the separate pieces applied to the treads or risers 45 to give many different effects. None of these could be obtained practically by the use of a single strip of carpet as has been employed in the past.

50 Other features and advantages of my invention will appear more fully as I proceed with my specification.

In those forms of devices embodying the features of my invention shown in the accompanying drawings—

55 Figure 1 is a plan view of a piece of carpet and pad with a backing; Fig. 2 is a view taken as

indicated by the line 2 of Fig. 1; Fig. 3 is a view taken as indicated by the line 3 of Fig. 1; Fig. 4 shows the same applied to the tread of a stairway; Fig. 5 is a top plan view of a piece of carpet and pad; Fig. 6 is a view taken as indicated by 5 the line 6 of Fig. 5; Fig. 7 is a view showing the same applied to the tread of a stair; Fig. 8 is a view similar to Fig. 6, showing the pad only; and Fig. 9 is a view of a stairway, showing the use of separate pads and a continuous strip of carpet. 10

One of the principal features of my invention is the provision of a metallic holding or binding member to be used at the edge of a piece of carpet or pad to hold the carpet and pad together or to hold the carpet, pad and backing material 15 together, or else to hold the edge of the pad alone. By means of such metallic member, the attaching of the carpet or pad is greatly facilitated.

I shall first describe the disclosure in Figs. 1 to 4, inclusive, of the drawings. As here shown, 20 10 indicates a rectangular piece of carpet, the base thereof being indicated by 10^a and the nap, by 10^b. Under this carpet is a rectangular pad 11 somewhat smaller in size and under the pad 25 is a sheet of backing material, for example, canvas 12, which is substantially the same size as the carpet. Under the front and back edges of the backing 12 is a strip of metal 13 provided with upwardly projecting prongs 14 extending 30 through the base 10^a of the carpet and clinched thereover. These prongs are short enough so that when they are clinched, they are hidden in the nap 10^b. The prongs 14 may be formed by cutting triangular holes 15 in the strips 13 and 35 bending the cut portion upwardly, leaving the same attached at one edge. These holes 15 may then be used for application of the tacks or nails 16 to attach the unit to the stair tread 17. If desired, of course, the nails 16 may be driven 40 right through the strips 13, which may be made of suitably soft metal.

I prefer to apply a few wire staples 18 to fasten the pad 11 and backing 12 together to prevent the former from slipping out of place. 45

It will be seen that, as shown in Figs. 1 to 4, I have formed a unit comprising a rectangular piece of carpet with a pad fastened thereto under the same. The pad is located between the backing and the carpet and the metal strips attaching 50 the edges of the backing and carpet together keep the pad between them. This unit may be applied to a stair tread, as shown in Fig. 4, by using the tacks or nails 16. When so applied, the strips 13 are entirely hidden from view. If de- 55

sired, the treads 19 may be covered with rectangular pieces of carpet 20 by means of the tacks 21. As stated above, the carpet 20 may be of the same color and material as the carpet 10 or may be 5 different in this or other respects. If desired, it is obvious also that the pieces of carpet 20 may be entirely omitted from the risers and the treads 17 only covered.

I shall now describe the device of Figs. 5, 6 10 and 7. As here shown, I employ a different kind of strip from the strip 13 shown in Figs. 1 to 4. As here shown, the metal strip used is indicated by 113 and is bent double along a substantially median longitudinal line so as to form said strip 15 into a sort of clamp. The inner edges are bent inwardly, as indicated by 113^a and 113^b to form a clamping effect. The strip is provided with suitable holes 115 and 115^a for the reception of tacks or nails. As shown in Figs. 5, 6 and 7, 110 indicates, in general, a rectangular piece of carpet. Below this is a pad 111 of substantially the same 20 size and shape. The front and back edges of the carpet and pad are fastened together by the clamping strips 113, as shown in Figs. 6 and 7. The carpet and pad thus form a single unit that 25 may be applied to the tread 117 of a stairway, as shown, by means of the tacks or nails 116.

I shall now describe the device of Figs. 8 and 9. As here shown, strips 213 are shown similar to the 30 strips 113. Instead of using these strips to fasten together the edge of adjacent pieces of carpet and pads, I employ the same upon the edges of a pad 211 alone. A plurality of such pads may then be attached to the treads 217 of a stairway,

as shown in Fig. 9, by the tacks 216. Over the pads thus attached may be placed a single strip of carpet 210 in the well-known manner to cover the entire stairway.

The pieces of carpet used in the devices of Figs. 5 10 to 4, inclusive, may have their edges bound, or rubber-backed carpet may be used. In the device of Figs. 5, 6 and 7, the strips 113 serve to bind the edges of the carpet so that no binding is necessary.

While I have shown and described certain embodiments of my invention, it is to be understood that it is capable of many modifications. Changes, therefore, in the construction and arrangement may be made without departing 15 from the spirit and scope of the invention as disclosed in the appended claim, in which it is my intention to claim all novelty inherent in my invention as broadly as permissible, in view of the prior art.

What I claim as new and desire to secure by Letters Patent, is:

A unit adapted for attachment to the tread of a stairway, including; a rectangular piece of carpet; a piece of backing material of substantially the same size and shape under the carpet; means for attaching the front and back adjacent edges of the carpet and backing material together, said means including a metal strip under the backing material with upwardly projecting 25 prongs clinched over the carpet base and hidden in the nap of the carpet; and a pad between the carpet and backing material.

KENNETH J. MCKENZIE.
